UNITED STATES PATENT OFFICE.

JACKSON L. KAIL, OF CHICAGO, ILLINOIS, ASSIGNOR, BY MESNE ASSIGNMENTS, TO WINSLOW BROS. COMPANY, OF CHICAGO, ILLINOIS, A CORPORATION OF ILLINOIS.

DOOR-HANGER.

1,232,563.

Specification of Letters Patent. Patented July 10, 1917.

Application filed February 1, 1915. Serial No. 5,340.

To all whom it may concern:

Be it known that I, JACKSON L. KAIL, a citizen of the United States, residing at Chicago, in the county of Cook and State 5 of Illinois, have invented a certain new and useful Improvement in Door-Hangers, of which the following is a full, clear, concise, and exact description, reference being had to the accompanying drawings, forming a 10 part of this specification.

The present invention relates to door hangers.

Sliding or rolling doors present many advantages in building construction and the 15 like, but proper installation of the same has been secured only where great care and accurate workmanship have been exercised.

It is an object of the present invention to provide an improved hanger for doors which 20 will secure to a maximum degree the advantages of a sliding or rolling door and which will allow of accurate, quick and convenient installation with a minimum of difficulty. The invention also provides means for 25 curing continuously successful and satisfactory operation after the door is installed. It is a further object to provide means for adjusting the height of the door to facilitate alinement of the door with the opening.

30 In Figure 1 I have shown an elevational view with parts broken away to show the location of the hangers on the top of the door and with their rollers resting in the track provided over the door.

35 Fig. 2 is a sectional end view of the hanger.

Fig. 3 is another end view of the hanger.

Fig. 4 shows a plan view of a modification with a different adjusting means.

40 Fig. 5 is an elevational view of the same.

Fig. 6 is a side elevational view of another modification.

Fig. 7 is an end view of the same; and

45 Fig. 8 is a sectional view taken on the lines 8, 8, of Fig. 6.

I provide a base or bracket which at its lower end is provided with countersunk holes for the reception of the holding screws 2 and 3, which fasten the hanger to the door-frame 4. At its upper end the bracket 1 is provided with a cylindrical lug or projec-

tion 5, which is provided with corrugations 6 adapted to fit into similar corrugations on the arm 8 of the roller-supporting portion of the hanger. A screw 9 binds the elements 5 and 8 together, and a set-screw 10 is adapted to bear upon the screw 9 and hold it in position so that when a certain position of the door is decided upon that adjustment may be secured, the double-screw holding 60 means insuring a permanence of adjustment. The corrugations 6 and 7 prevent slipping and aid in the proper adjustment of the door, as will be described later.

The arm 8 is fashioned into a hollow ring 65 11 at one end. The outer periphery of this ring, 12, is cylindrical, but the inner periphery, 13, is grooved to provide a race for the ball bearings 14. The roller is composed of two halves 15 and 16 (best shown in Fig. 70 2), which are placed upon opposite sides of the ring 11 and are secured together by means of the screw 17. A screw 18 is provided to prevent relative angular displacement of the two elements 15 and 16. The 75 adjoining surfaces of the two elements are angularly recessed adjacent their peripheries as indicated at 19 and 20 to provide a channel bearing surface for the ball bearings 14. The peripheries of the sections 15 and 16 of 80 the roller are beveled as at 21 and 22 to readily engage the grooved trackway 25, the latter being mounted over the door by an angle iron 25' which is in turn retained in supporting position by means of a rivet 28. 85

The outer edge of the roller is rounded or beveled as hereinbefore described; that is to say, the outer surface of the roller approximates the surface of a sphere or of an oblate spheroid of approximately the same 90 curvature as that of the groove or channel in the track 25. From this it will be apparent that even if the plane of the roller and the plane of the track do not coincide, such skewing of the roller will have a minimum detrimental effect and will not cause a grinding noise, as is common in flanged rollers, nor will there be the same tendency to jump the track. It will be seen that in the construction of Figs. 1, 2 and 3 the same 100 bracket and roller serve for both ends of the door. By means of the elbow construc-

tion it is possible to have the rollers at or even beyond the extreme edges of the door. This gives an elongated base of support, reducing the tendency of the door to tilt or 5 skew.

- The adjusting and fastening screws are all arranged on the bracket side so that they will occupy a minimum thickness and will at the same time be accessible.
- 10 It will be evident that when the bracket 1 is secured to the door-frame the roller-bearing arm 8 will be movable about the pivot 9 until the latter is tightened. Often after a door is hung it is found that it is not hanging straight, one of the door ends being higher or lower than the other end. My invention provides a means for securing the proper adjustment of the door without having to take the door down. For such adjustments the corrugations 6 and 7 are provided, so that when the screws 9 and 10 are loosened, a slig' t rotation for one or two notches will result in the raising or lowering of the door. When the door has been raised 25 or lowered the desired extent the screws 9 and 10 are once more tightened and a lasting adjustment is secured.

In Figs. 4 and 5 I have shown a modification of the adjusting means. Here the rear end of the arm 8 is provided with a projection 30. The bracket 1 is also provided with a projection or ear 31, through which a bolt 32 passes and engages with the lug 30. A nut 33 is placed upon the screw-bolt for the purpose of locking the bolt 32. It will be evident that this modification provides means for obtaining a finer adjustment of the height of the door than that shown in Figs. 1, 2 and 3. If the hanging 40 of the door is found to be faulty, as having one end higher or lower than the other, or it is desired to have the entire door raised or lowered, it is only necessary to manipulate the bolt 32 properly in order to effect 45 the desired result.

In Figs. 6, 7 and 8 I have shown another modification of the hanger. Here the connection between the base element 1 and the roller-bearing arm 8 is a rigid one and not 50 pivoted, as above described. I have here shown the lug 5 of the bracket 1 as rectangular in shape and provided with corrugations 6 which are horizontal and parallel. The arm 8 of the roller-supporting portion of 55 the hanger is provided with corrugations adapted to fit into the corrugations 6 of the bracket. The arm 8 is provided with a flange 35 which bears against the edge of the lug 5 and tends to hold the elements 5 and 8 in alinement. Screws 9 and 10, similar to those before described, are provided to secure together the elements 5 and 8.

The roller shown in Fig. 8 is of somewhat

more unitary and economical construction than that before described. It is composed 65 of the two halves 15 and 16 which halves are of such construction that they may be stamped or pressed out of sheet metal. The inner periphery of the hollow ring 11 provides a race for the ball bearings 14, as before described.

This construction of the roller provides one of practically maximum strength for a section taken through it, as shown in Fig. 8, will be seen to be not unlike that of an I 75 beam which is the section of greatest strength.

It will be seen that the adjustment provided by the horizontal corrugations shown in this modification is a finer one than that 80 provided by the radial corrugations. Here for each difference in elevation of the corrugations themselves the roller will be raised or lowered the same amount so that the door is raised and lowered a distance exactly 85 equal to that made at the corrugations themselves. In the case of the radial corrugations, for a rotation of one corrugation, the center of the roller portion will move on the arc of a circle whose center is at the center of 90 the radial corrugations and the door will be raised or lowered a correspondingly larger amount, due to this arrangement, than for a variation of one corrugation where the same are horizontal and parallel, and therefore a nicer adjustment of the door is obtained 95 by means of the latter.

It is to be noted that instead of ball bearings, roller bearings or a plain cylindrical or 100 any other bearings may be provided.

It will be noted that the ring 12 rides above the surface of the groove in the track 25. This allows a space for the dust to accumulate without coming under the surface of the roller. Periodical brushing of the 105 track will thus keep the track and rollers constantly clean.

The above described embodiment illustrates only typical forms in which my invention may appear. I do not intend to be 110 limited to these specific forms and numerous modifications will at once be suggested to those skilled in the art. I desire that my invention be construed as broadly as is consistent with the spirit and scope of the ap- 115 pended claim.

What I claim is:

In combination, a trackway comprising a solid bar with a semi-circular groove in its upper face, an object carrying arm provided 120 with a bearing, located centrally over said groove, a roller having a double running surface, one tread thereof engaging one side of said groove and the other tread engaging the other side of said groove, said treads being 125 of greater diameter than the bearing

and conforming to the shape of the groove whereby to prevent lateral displacement of the roller on the trackway and to provide a space at the deepest point of the trackway which is not in contact with the roller, to receive dust, dirt, and the like.

In witness whereof, I hereunto subscribe

my name this 21st day of January A. D. 1915.

JACKSON L. KAIL.
